UNITED STATES PATENT OFFICE.

HARRY C. SCHAPEE, OF ST. LOUIS, MISSOURI.

DESK BLOTTER.

Application filed September 22, 1925. Serial No. 57,901.

This invention relates to new and useful improvements in desk blotters, the objects being to provide a device containing a roll of blotting paper and operative to discharge the used blotting portion of the paper and bring in position a clean portion thereof.

Further objects of the invention are to provide a blotting device having suitable mechanism which can be manually operated to discharge a section of the blotting paper and cause a clean section thereof to be placed in blotting position.

Other objects of the invention are to provide a device of the class described which is both ornamental and useful, being of neat appearance and of practical construction to permit easy manipulation thereof, which is efficient in performing its intended functions, and can be economically manufactured.

With these and other objects in view, my invention consists in certain novel features of construction and arrangement of parts, hereinafter more fully described and claimed, and illustrated in the accompanying drawings, in which—

Figure 1 is a perspective view of a blotting device.

Figure 2 is a longitudinal cross section 30 through the casing and showing the mechanism of the device in side elevation.

Figure 3 is a top plan view of the mechanism and showing the casing in horizontal cross section.

Figure 4 is a transverse cross section taken on lines 4—4 of Figure 2.

Figure 5 is a detail view showing the ratchet mechanism of the feed roller.

Referring by numerals to the accompanying drawings, 10 indicates a casing of suitable dimensions to permit easy manipulation of the device, and open at the bottom to expose a blotting paper. This casing is shaped to fit the palm of the user's hand, having a convex upper portion 10^a and reduced or depressed side wall portions 10^b. Within this casing is arranged a frame or support 11 which is secured thereto by rods 12 passing through apertures formed in the side walls of casing 10 and through apertures formed in lugs 14 which are formed integral with support 11 and projecting longitudinally therefrom.

Each rod 12 is provided at one end with a head 12^a and the opposite end of said rod is screw-seated in a threaded opening of a

knurled nut or removable head 12^b so that said support can be removed from the casing by unscrewing nut 12^b and withdrawing rod 12 from position. Support 11 is provided near each end with a pair of upstanding lugs 15 disposed on each side of said support adjacent to the corresponding side walls of casing 11. A vertically disposed slot 16 opening at the top is formed in each lug and the forward pair of lugs receives the trunnions of a pair of cooperating rollers 17 and 18, while the rear pair of lugs receives the trunnions of a pair of cooperating rollers 19 and 20.

The trunnions of rollers 17 have bearings in the lower ends of slots 16 of the forward pair of lugs 15, while roller 18 is disposed above roller 17 and rests thereon, the trunnions of roller 18 being arranged in the upper end of slot 16 serve to maintain said roller 17 in position, at the same time permitting vertical movement thereof. The trunnions of roller 19 have bearings in the lower ends of slots 16 of the rear pair of lugs 15 and trunnions of roller 20 occupy the upper ends of slots 16 with said roller resting on roller 19.

Each pair of rollers is held in cooperative relation by means of springs 21 which are anchored intermediate their ends to lugs 22 arranged between lugs 15 and projecting upwardly from support 11. These springs are secured to lugs 22 in any suitable manner, such as screws 24, and the ends of said springs bear on the trunnions of upper rollers 18 and 20, respectively, and yieldingly hold said rollers in operative engagement with their respective lower rollers.

A roll A of a strip of blotting paper of proper width is disposed in support 11 between lugs 22 and one end of the strip is passed between rollers 18 and 17, thence downwardly over the curved forward end 25 of the bottom 26 of support 11 and then passes rearwardly under a pad 27 of felt or other suitable material, which pad is secured to a raised portion 26^a formed on the bottom wall 26. Said strip is then turned inwardly over the curved rear end 25^a of bottom wall 26 under roller 19, passes over said roller, being held in engagement therewith by roller 20 and terminates adjacent to the beveled edge B of the rear end wall 10^a of casing 10.

The peripheral face of roller 19 is preferably covered with sand-paper or other

suitable covering 28 in order to insure efficient frictional engagement between the strip of blotting paper and roller 19 when the latter is actuated. This roller is manually operated by means of a knurled knob 29 secured to one end of trunnion 19^a, which latter is formed longer and projects beyond lug 15 through a slot 30 formed in one of the side walls of casing 10. By turning said knob, roller 19 is actuated in the direction indicated by the arrow, thereby moving said strip of blotting paper as indicated by arrows and discharging the used portion of said paper past the beveled edge B of wall 10^a. When the desired fresh portion of blotting paper has been brought into blotting position, that portion which projects beyond the edge B is torn away as indicated in Figure 2.

In order to prevent rotation of roller 19 in the opposite direction, which might cause buckling of the paper positioned against the pad 27, trunnion 19^a has fixed thereto a ratchet wheel 31 and engaging the teeth of said wheel is a spring-pressed pawl 32 which locks said roller 19 against backward rotation. Pawl 32 is preferably formed by bending one end of a spring 33 to proper shape for engagement with the teeth of wheel 31 and securing the opposite end of said spring 33 to one of the lugs 22 as indicated at 33^a.

The interior of casing 10 is of ample dimensions to accommodate a roll of blotting paper of suitable size so that it is only necessary to renew the roll at long intervals. The bottom wall 26, as well as the pads 26^a and 27 and the lower edges of casing 10, are convex longitudinally so as to permit rocking movement of the blotting device when in use.

Generally, each roll of paper is wound on a tube such as 34 and in locating the roll in the support said roll is preferably placed between lugs 22, and a rod 35 removably seated in said lugs is passed through said tube to hold said roll in position.

My improved desk blotter is of simple construction, can be easily operated to bring a fresh portion of the blotting paper in position and discharge the used portion.

While I have shown and described the preferred form of my invention, it is obvious that various changes in the construction of my device can be made without departing from the spirit thereof.

I claim:

1. A blotting device comprising a casing provided with an open bottom, a support disposed within said casing, and a pair of spring pressed cooperating rollers arranged

in each end of said support, and adapted to feed a strip of blotting paper over the exposed bottom of said support, one of said rollers being manually operable and having roughened peripheral surface for increasing the engagement between said roller and said strip of blotting paper.

2. A blotting device comprising a casing provided with an open bottom, a support disposed within said casing, a pair of spring pressed cooperating rollers arranged in each end of said support and adapted to feed a strip of blotting paper over the exposed bottom of said support, one of said rollers being manually operable and having roughened peripheral surface for increasing the engagement between said roller and said strip of blotting paper, and a ratchet and pawl mechanism for cooperating with said manually operable roller to permit rotation thereof in one direction only.

3. A blotting device of the class described comprising a support adapted to receive a roll of blotting paper, a pair of cooperating rollers arranged at one end of said support for feeding said paper over the bottom of said support, a pair of cooperating rollers arranged at the opposite end of said support for discharging said paper, and means for actuating the last mentioned pair of rollers in one direction only.

4. A blotting device of the class described comprising a support adapted to receive a roll of blotting paper, a pair of cooperating rollers arranged at one end of said support for feeding said paper over the bottom of said support, a pair of cooperating rollers arranged at the opposite end of said support for discharging said paper, means for actuating the last mentioned pair of rollers in one direction only, and springs for maintaining each pair of rollers in operative engagement with said paper.

5. In a device of the class described, a support provided with a longitudinally convex bottom, upstanding vertically slotted lugs arranged on each side of said support near each end thereof, a pair of superimposed rollers disposed transversely of each end of said support and provided with trunnions having bearings in the slots of said lugs, springs secured to said support and having their free ends bearing on the trunnions of the upper roller of each pair for maintaining said rollers in pressure engagement, and means for actuating said rollers to move a strip of blotting paper over said convex bottom and discharge it at one end of said support.

In testimony whereof I hereunto affix my signature this 19th day of September, 1925.

HARRY C. SCHAPER.
